UNITED STATES PATENT OFFICE

OTTO JOSEPH LAUTERBACH, OF NEW ORLEANS, LOUISIANA.

TIE-CLASP.

1,196,251.

Specification of Letters Patent. Patented Aug. 29, 1916.

Application filed August 26, 1915. Serial No. 47,439.

To all whom it may concern:

Be it known that I, OTTO J. LAUTERBACH, a citizen of the United States, residing at New Orleans, in the parish of Orleans and 5 State of Louisiana, have invented certain new and useful Improvements in Tie-Clasps; and I do declare the following to be a full, clear, and exact description of the invention, such as will enable others skilled in the 10 art to which it appertains to make and use the same.

This invention relates to improvements in clasps and more particularly to tie clasps.

The object of the invention is to provide 15 a simply constructed and ornamental device of this character which may be readily applied and removed.

Another object is to provide a clasp having a tongue constructed to provide two 20 gripping elements one of which operates as a fulcrum for releasing the other.

With these and other objects in view the invention consists of certain novel features of construction, combination and arrangement of parts as will be more fully described 25 and claimed.

In the accompanying drawings: Figure 1 represents a front view of this improved clasp; Fig. 2 is a side or edge view thereof; 30 Fig. 3 is a rear elevation; Fig. 4 is a longitudinal section taken on the line 4—4 of Fig. 3; Fig. 5 is a transverse section taken on the line 5—5 of Fig. 3. Fig. 6 is a side elevation showing the free arm ends pressed 35 toward each other for moving the free end of the tongue outward. Fig. 7 is a transverse section taken on the line 7—7 of Fig. 3.

In the embodiment illustrated a clasp 1 is shown constructed of a resilient metal 40 strip of any desired width and any desired metal being preferably gold or silver plated and which is bent transversely intermediate of its ends preferably at a point to provide arms 2 and 3 of different lengths, the arm 45 2 being longer than arm 3 and constituting the front or exposed face of the clasp. This arm 2 is preferably decorated or ornamented, the initials of the owner being here shown in cut out or filigree work.

50 The shorter arm 3 which constitutes the back of the clasp has a longitudinally extending tongue 4 struck out therefrom by forming parallel laterally spaced slits 5 and 6 in the plate constituting said arm 2 and 55 then slitting said plate transversely at the

inner end of the arm, said transverse slit 7 connecting the longitudinal parallel slits and thus forming the free end of the tongue 4. The base of this tongue 4 is disposed adjacent the free end of the arm 2 as is shown clearly in Figs. 2 and 3. This tongue 4 adjacent its base is bent laterally inward toward and into contact with the arm 2 and then bent outwardly forming a loop 8 which is designed to span the space between the arms 2 and 3 and to normally engage the inner face of the front arm 2 and in connection therewith to form clamping members between which a tie and the shirt to which it is designed to be fastened is designed to be passed. This tongue 4 is then extended in substantially the same plane as arm 3 and the free end thereof is also bent laterally inward and provided with penetrating prongs or spurs 9 which are also of a length 60 corresponding to the space between the arms 2 and 3 which space is controlled by the size of the loop 8 at the base of the tongue. These prongs or spurs 9 are also designed 65 as gripping or fastening elements being adapted to penetrate the shirt bosom to which the tie is to be attached and thus holding the clasp firmly in position on the shirt while the loop 8 serves to yieldingly clamp the tie and shirt together. This loop 8 also 70 forms a fulcrum for the tongue 4 and when the free ends of the arms 2 and 3 are pressed toward each other as shown in Fig. 6 the spur carrying end of said tongue will be forced outwardly and released from its 75 engagement with the shirt and thus permit said clasp to be readily removed.

From the foregoing description it will be obvious that the loop 8 performs the double function of a clamping element for connecting a tie with a shirt and also as a fulcrum for the tongue thus facilitating the attachment and removal of the clasp.

I claim as my invention:

A clasp comprising a resilient metal strip 100 bent transversely intermediate its ends to form spaced arms, one of said arms having a longitudinally extending tongue struck therefrom with its base arranged near the free end of said arm, said tongue being bent 105 laterally inward toward the other arm into contact therewith and then bent outwardly and extended in substantially the same plane as the arm from which it is struck with its terminal bent laterally inward toward the 110

other arm whereby the bent portion at the base of the tongue forms a combined clamping member and fulcrum to provide for the movement of the bent terminal of said tongue away from the arm with which it normally contacts when the free ends of said arms are pressed toward each other.

In testimony whereof I have hereunto set my hand in presence of two subscribing witnesses.

OTTO JOSEPH LAUTERBACH.
